MARINE REVERSE GEAR

Clarence H. Barton and Charles Drexler, Indianapolis, Ind., assignors to L. G. S. Devices Corporation, Indianapolis, Ind., a corporation of Indiana

Application April 25, 1931, Serial No. 532,751

9 Claims. (Cl. 74—379)

This invention relates to improvements in marine reverse gears and it consists of the matters hereinafter described and more particularly pointed out in the appended claims.

5 The primary object of the invention is to provide a simple and efficient reverse gear for motor boats and the like which includes a means permitting an overrunning of the driven shaft of the gear when the driving shaft of the gear rotates at a speed slower than that of the driven

10 shaft. A further object of the invention is to provide a gear of this kind which when in forward, leaves all gears employed in providing reverse, passive 15 and non-rotating, thus providing a more silent mechanism with no substantial churning and resulting heating of the lubricant in the casing of the gear.

15 These objects of the invention as well as others, together with the many advantages thereof will more fully appear as we proceed with our specification.

In the drawings:—

Fig. 1 is a longitudinal vertical sectional view 25 through a reverse gear embodying the preferred form of the invention and with the parts in neutral position wherein no power is being transmitted from the driving shaft to the driven shaft.

Fig. 2 is a fragmentary longitudinal sectional 30 view through the gear case with the parts shown therein in a position for reverse drive.

Fig. 3 is a view similar to Fig. 2 with the parts in a position providing a forward direct drive.

Fig. 4 is a transverse vertical sectional view 35 through the gear as taken on the line 4—4 of Fig. 1.

Fig. 5 is a detail longitudinal vertical sectional view on an enlarged scale through a part of an overrunning clutch employed in the gear and 40 which will be more specifically referred to later.

Referring now in detail to that embodiment of the invention, illustrated in the accompanying drawings:—1 indicates as a whole the open top casing for the reverse gear which includes an inclined bottom wall 2, upright side walls 3 and 4 and a rear wall 5 and said casing is formed at its front end for a bolted on attachment to an engine 6 which includes a crank shaft 7. The rear wall 5 of the casing includes a tubular extension 8 and near the front end of said casing is provided an upright annular bearing plate 9. The open top of the casing is closed by a cover 10, suitably bolted thereto.

11 indicates a tubular shaft that engages at 55 its front end in a recess in the associated rear

end of the crank shaft 7 and a transverse pin 11^a secures these shafts together. The shaft 11 constitutes the driving shaft of the gear and is provided at its rear end with relatively short external clutch teeth 12 and is provided at its front end with relatively long external splines 13.

14 indicates the tail or driven shaft of the gear which is formed midway of its ends with longitudinally spaced sets of clutch teeth 15 and 16. Said teeth are full depth teeth and connecting 10 the same are dedendum teeth 17. The teeth 15—16 and 17 are each cut or otherwise formed as a continuous tooth. Forward of the teeth 15 is the collar receiving portion 18 of said shaft which portion includes an extension 19 of reduced 15 diameter having a bushed bearing in the rear end of the driving shaft 11. To the rear end of the shaft 14 is splined a flanged fitting 20 for attachment to the propeller shaft of the boat.

In the tubular extension 8 of the rear wall 5 is located a retainer 21 for an antifriction bearing 22 in which shaft 14 is journalled. A stuffing box 23 surrounds the barrel portion of the fitting 20 and a part of said box is secured to the extension 8 by the same bolts 24 that secures the 20 retainer 21 thereto.

25 indicates a cup shaped friction clutch member having a hub 26 operatively engaged on the splined part 13 of the driving shaft 11. Coacting therewith is a second friction clutch member 27, the front end part 28 of which embraces the clutch member 25 and is provided with external clutch teeth 29. The clutch members 25 and 27 are relatively rotatable but are held against endwise separation by a thrust washer 30 and spring locking ring 31, when endwise movement is imparted to said members as will later appear. The rear end part 32 of the clutch member 27 is of reduced diameter and is there provided with internal dedendum teeth 33 and an 35 external annular shoulder or rib 34. Between said end parts 32 and 28 of the clutch member 27, parts 35 and 36 of intermediate diameters are provided so that the said clutch member may be said to be stepped down in diameter 40 from one end to the other. In the part 34 of intermediate diameter is a longitudinal slot 37 the purpose of which will presently appear.

Associated with and surrounding the rear end 45 part 32 of the clutch member 27 is a sleeve or collar 38 having external clutch teeth 39 at its front end and internal clutch teeth 40 at its rear end which normally engage with the dedendum teeth 17 on the tail or driven shaft 14 when the gear is in neutral. This sleeve or collar while 50 55

rotative relative to said part 31 of the clutch member 27 is held against endwise separation with respect thereto by means of a spring locking ring 40 that engages the annular shoulder 5 33 before mentioned.

Associated with the sleeve or collar 37 and journalled in the rear end wall 5 of the casing is a bevel gear 41 provided near its front end with internal clutch teeth 42 adapted for engagement 10 by the teeth 38 as will later appear. Associated with and journalled in the bearing plate 9 is a second bevel gear 43 provided near its rear end with internal clutch teeth 44 adapted for engagement 15 by the teeth 29 of the clutch member 27 as will later appear. When the parts of the reverse gear as a whole, are in neutral, the teeth 38 are spaced closer to the teeth 42 of the bevel gear 41, than are the teeth 29 with respect to the teeth 44 of the gear 43. Thus in the rearward 20 movement of the clutch member 27, the teeth 38—42 engage a little in advance of the engagement between the teeth 29—44.

On each side wall 3 and 4 is provided an inwardly extending tubular stud 45 upon which is journalled a bevel pinion 46, both pinions 46 being 25 in constant mesh with opposite sides of the bevel gears 41—43. In each stud 45 is a spring pressed 30 detent pin 45^a for a purpose soon to appear.

The clutch members 25—27 coact to provide a 35 chamber or pocket 47 to receive a main clutch spring 48. This clutch spring is of such diameter as to normally have a slight clearance with respect to said chamber or pocket and the rear end of said spring has an axially extending toe 49 that is anchored in the clutch member 27. The front end of said spring has a radially in- 40 turned toe 50.

Within the main clutch spring 48 is located a 45 clutch sleeve 51 which surrounds the front end portion of a coaxing clutch sleeve 52 and the rear end of said clutch sleeve 52 bears upon that part 18 of the driven shaft between the teeth 15 and its front end extension 19. In the rear 50 end of said clutch sleeve 52 is provided an annular external groove 53 and on the front end of said sleeve are short internal clutch teeth 54 adapted for engagement with the clutch teeth 12 of the shaft 11 when said sleeve is moved rearward the desired distance. While the clutch sleeves 51—52 are relatively rotatable they are held against separation by a spring ring 55 best shown in Fig. 5.

The said clutch sleeves 51—52 coact to provide a 55 chamber 56 to receive a secondary or energizing clutch spring 57 which is normally of a diameter to be oversize with respect to said chamber. The rear end of said spring 57 is anchored to the clutch member 52 while the toe 50 on the like end of the main clutch spring 48 extends 60 into a longitudinal groove 51^a in the sleeve 51.

A shift collar 58 having an external annular groove 58^a slides on the part 35 of the clutch member 27 and carries an inwardly extending pin 59 at the rear end which normally projects through the longitudinal slot 36 into the groove 53 of the 65 clutch member or sleeve 52.

In the cover 10 is mounted a transverse shaft 60 to which a rocking movement may be imparted in any suitable manner. Fixed to this rock shaft 70 is a yoke 61 including diverging arms, each carrying a pad 62 engaging in diametrically opposite sides of the annular groove 58^a in the shift collar 58. Each arm of the shifter yoke 61 is provided at its bottom end in its exterior face, 75 with a plurality of spaced notches 63 in the de-

sired one of which the associated spring pressed pin 45^a before mentioned is adapted to engage to yieldingly hold the shifter yoke either in neutral or in the forward or reverse position into which it has been shifted.

In Fig. 1 the parts of the gear are shown in neutral position. Even with the shaft 11 being driven, no power is transmitted to the driven or tail shaft because the main clutch spring 48 is not at this time in clutching engagement.

To shift the gear described, into forward, rocking movement is imparted to the shaft 60 to swing the yoke 61 forwardly as shown in Fig. 3 and this of course, will shift the collar 58 in a like direction. By reason of the pin 59 carried by said collar, the clutch member 27 and clutch sleeve 52 are shifted forwardly. This will engage the teeth 54 of the sleeve 52 with the teeth 13 on the driving shaft 11, with a resulting rotation of said sleeve 52. As said sleeve 52 is rotated it will act to 20 unwind the energizing spring 57 which radially expands to clutch the sleeves 51—52 together. As the front end of the sleeve 51 has the like end of the main clutch spring 48 operatively connected thereto through the toe 50 and groove 51^a, 25 said spring is unwound and radially expanded to clutch the clutch members 25—27 together. In the rotation imparted to the sleeve 51 it is pointed out that this radial expansion of the main clutch spring 48 is transmitted from one end to the other 30 thereof progressively through all of the turns thereof so that a positive clutching action is 35 established.

In this shifting of the clutch members, the teeth 32 of the clutch member 27 are caused to engage 40 the clutch teeth 15 on the driven shaft 14 so that now the drive is from the shaft 11 to the clutch member 25 to the clutch member 27 (through the clutch spring 48) and from said clutch member 27 through its teeth 32 to the teeth 15 of the shaft 45 14 which is the driven shaft of the gear. As the fitting 20 is splined to the rear end of the driven shaft, it is apparent that the propeller shaft before mentioned as adapted for operative connection to said fitting is likewise driven. Thus the 50 driven shaft is being driven at the same speed and in the same direction as the driving shaft.

To return the parts to neutral, the shaft 60 is 55 rocked in the other direction and this of course, imparts a rearward shift to the collar 58. In the initial movement of the collar, the pin 59 moves toward the rear of the slot 36 without causing movement of the clutch 27 but it does withdraw the teeth 54 of the secondary clutch sleeve 52 from the teeth 13 of the driving shaft, thus relieving the drive into the spring 57. Said spring becomes deenergized and in turn deenergizes the main clutch spring 48 which immediately returns to its normal condition wherein it has clearance 60 with respect to its chamber 47. Thus driving connection is released between the clutch members 25—27.

To provide reverse, further rearward shift of the collar 58 will through the pin 59 cause the clutch members 27 and 25 to move rearwardly, bringing the teeth 38 on the sleeve 37 into engagement with the teeth 42 of the bevel gear 41. Simultaneously therewith the teeth 39 on said sleeve will engage the clutch teeth 16 of the driven shaft and immediately thereafter, the teeth 29 70 on the front end of the clutch member 27 are brought into engagement with the teeth 44 of the bevel gear 43.

Also during this shift of the collar 58, the secondary clutch sleeves 51—52 are moved rear- 75

wardly and this brings the teeth 54 of the sleeve 52 into engagement with the teeth 12 of the driving shaft. Thus the secondary clutch sleeve 52 is driven from the drive shaft and this energizes the spring 57 to clutch the secondary clutch sleeves together. When this occurs, the main clutch sleeve is energized and is caused to radially expand to clutch the main clutch members 25 and 27 together.

10 Thus the drive is now from the shaft 11 to the clutch members 25-27 to the bevel gear 43 and from this gear to the idler pinions 46 to the bevel gear 41. As the sleeve 38 is operatively engaged with said gear 41 through the teeth 38-42 and as the teeth 39 of this collar are in engagement with the teeth 16 of the driven shaft, it is apparent that the driven shaft is being driven in a reverse direction from the driving shaft without a relative speed reduction.

15 20 To shift back into neutral, the collar 58 is shifted forwardly. As the pin 59 carried thereby is at the rear end of the slot 36 in the clutch member 27, it is apparent that in the initial part of the movement of the collar, the secondary clutch sleeves are first moved forwardly and this disengages the teeth 54 of the sleeve 52 from the teeth 12 of the driving shaft. This first de-energizes the clutch spring 57 and then the main clutch spring 48 so that driving connection be- 25

30 35 30 To shift back into neutral, the clutch members 25-27 are moved forwardly disconnecting the teeth 29 from the teeth 44 of the bevel gear and at the same time shifting the sleeve 37 forwardly, disconnecting the teeth 38 of the same from the teeth 42 of the bevel gear 41. In this movement of the sleeve 37, the teeth 39 thereof are disengaged, from the teeth 16 on the driven shaft.

40 45 40 It is apparent that by means of the reverse gear described, the drive in either forward or reverse is through the action of a clutching spring. Thus when approaching a dock or landing in a boat equipped with our improved gear, it is possible to reduce the speed of the engine and this will permit the driven shaft to overrun the driving shaft so that the propeller will not act as a drag to slow down the movement of the boat in drifting under momentum to the dock or landing. Thus it is 50 not necessary to make so many shifts of the gear when landing or docking as is required in gears where such overrunning action is absent.

55 Thus the boat is better controlled in making such a landing or docking and the possibility of damage to the boat is materially reduced. Again, wear and tear on the gear is reduced along with the attending objectionable noises.

60 65 While in describing the invention, we have referred in detail to the form, arrangement and construction of the parts thereof, the same is to be considered merely as illustrative so that we do not wish to be limited thereto except as may be specifically set forth in the appended claims.

65 We claim as our invention:-

70 75 65 1. In a reverse gear of the character described, the combination of a driving shaft rotatable in one direction, a coaxial driven shaft rotatable in either direction, an overrunning clutch unit shift-able longitudinally of the shafts in either direc-tion and comprising a clutch member connected to be driven by the driving shaft, a relatively rotatable complemental clutch member and a spring between the two clutch members adapted in re-sponse to shift of the unit in either direction to change its diameter and to connect the two mem-

bers for drive one from the other, means be-tween the complemental clutch member and the driven shaft whereby when the unit is shifted in one direction said driven shaft is connected to the complemental clutch member for drive there-by in the same direction as the driving shaft, and reversing gearing between said complemental clutch member and the driven shaft whereby when the clutch unit is shifted in the other di-rection the driven shaft is reversely driven by said 10 complemental clutch member.

2. In a reverse gear of the character described, the combination of a driving shaft rotatable in one direction, a coaxial driven shaft rotatable in either direction, an overrunning clutch unit shift-able longitudinally of the shafts in either direc-tion and comprising a clutch member connected to be driven by the driving shaft, a relatively rotatable complemental clutch member and a spiral clutch spring between the two members, means 20 operable in response to shift of the clutch unit in either direction for energizing the clutch spring and causing the same to connect the two clutch members together for drive one from the other, means between the complemental clutch member 25 and the driven shaft whereby when the unit is shifted in one direction said driven shaft is connected to the complemental clutch member for drive thereby in the same direction as the driving shaft and reversing gearing between said complemental clutch member and the driven shaft whereby when the clutch unit is shifted in the other direction the driven shaft is reversely driven by said complemental clutch member.

3. In a reverse gear of the character described, the combination of a driving shaft rotatable in one direction, a coaxial driven shaft rotatable in either direction, an overrunning clutch unit shift-able longitudinally of the shafts in either direc-tion from a neutral position and comprising a 40 clutch member connected to be driven by the driving shaft, a relatively rotatable complemental clutch member shaped to form a clutch surface, and a spiral clutch spring between the two clutch members and operatively arranged with respect 45 to said surface, means for shifting said unit, en-ergizing means for the spiral clutch spring con-nected to said shifting means so that it operates in response to shift of the clutch unit in either 50 direction to cause the spring to engage the afore-said surface and clutch the two members together for drive one from the other, means between the complemental clutch member and the driven shaft whereby when the unit is shifted in one 55 direction said driven shaft is connected to the complemental clutch member for drive thereby in the same direction as the driving shaft and re-versing gearing between said complemental clutch member and the driven shaft whereby when the clutch unit is shifted in the other di-rection the driven shaft is reversely driven by said complemental clutch member.

4. In a reverse gear of the character described, the combination of a driving shaft rotatable in 65 one direction, a coaxial driven shaft rotatable in either direction, an overrunning clutch unit shift-able longitudinally of the shafts in either direc-tion from a neutral position and comprising a cup-like clutch member connected to be driven 70 by the driving shaft, a relatively rotatable, complemental, cup-like clutch member, and an ex-pansible type clutch spring between the two mem-bers, means for shifting the clutch unit, energiz-ing means for the clutch spring connected to 75

the shifting means so that it operates in response to shift of the clutch unit in either direction to expand the spring into clutched relation with the two clutch members so as to cause drive of the 5 complementary clutch member from the first mentioned clutch member, means between the complementary clutch member and the driven shaft whereby when the unit is shifted in one direction said driven shaft is connected to the complementary clutch member for drive thereby in the 10 same direction as the driving shaft and reversing gearing between said complementary clutch member and the driven shaft whereby when the clutch unit is shifted in the other direction the driven 15 shaft is reversely driven by said complementary clutch member.

5. In a reverse gear of the character described, the combination of a driving shaft rotatable in one direction, a coaxial driven shaft rotatable in 20 either direction, an overrunning clutch unit shiftable longitudinally of the shafts in either direction from a neutral position and comprising a cup-like clutch member connected to be driven by the driving shaft, a relatively rotatable, complementary, cup-like clutch member forming with the first mentioned clutch member a spring clutch 25 pocket and a main clutch spring disposed in the pocket, means including a secondary and energizing spring for expanding the main clutch spring 30 into gripping relation with the two clutch members when the clutch unit is shifted in either direction, means between the complementary clutch member and the driven shaft whereby when the unit is shifted in one direction said 35 driven shaft is connected to the complementary clutch member for drive thereby in the same direction as the driving shaft and reversing gearing between said complementary clutch member and the driven shaft whereby when the clutch 40 unit is shifted in the other direction the driven shaft is reversely driven by said complementary clutch member.

6. A reverse gear comprising in combination, a driving shaft rotatable in one direction and a 45 coaxial driven shaft rotatable in either direction and having longitudinal splines thereon, a clutch unit between, and shiftable longitudinally of said shafts and including two relatively rotatable clutch members, one of said clutch members being 50 operatively connected to the driving shaft, the other of said clutch members being splined and adapted for engagement with the splines on the driven shaft, means operating automatically in response to relative rotation of said clutch members 55 in one direction for clutching them together, a spline shiftable but relatively rotatable with respect to said other clutch member and adapted for engagement with the other spline on the driven shaft, means for shifting said clutch unit 60 in the desired direction, to cause said spline shiftable with said other clutch member to engage with said other spline on the driven shaft, and means operating automatically when said last two mentioned splines are so engaged for driving said

spline shiftable with said clutch member in a direction different from that of the driving shaft.

7. In a reverse gear, the combination of a driving shaft, a driven shaft, a clutch mechanism shiftable on said shafts and including a member 5 splined to the driving shaft and a second member relatively rotatable with respect thereto and adapted when in one position to be operatively connected to the driven shaft, a main clutch spring operative in a relative rotation of said 10 members in one direction for clutching said members together, means for shifting said clutch mechanism upon said shafts, an energizing spring for the main clutch spring and means actuated by said shifting means for operatively connecting 15 said energizing spring to said driving shaft for causing said main clutch spring to clutch said two clutch members together.

8. In a reverse gear comprising in combination a casing, a driving shaft and a driven shaft having 20 spaced splines thereon, spaced bevel gears journaled in the casing and so operatively connected together as to rotate in opposite directions, a clutch mechanism shiftable on said shafts and including two relatively rotatable clutch members, a main clutch spring for clutching said members together, one of said members having a splined connection with the driving shaft and the other clutch member having teeth at one end adapted for engagement with mating teeth on 25 said bevel gears and having teeth at the other end adapted for engagement with one of said splines on the driven shaft, a spline longitudinally movable but rotative with respect to said other clutch member and adapted when said clutch 30 member is in one limit of its movement for engagement with said other bevel gear and the other spline on the driving shaft, means for shifting said clutch mechanism and means operative when said clutch mechanism has been shifted 35 to its limit in either direction for energizing the main clutch spring from the driving shaft to clutch said two members together.

9. In a reverse gear of the character described the combination of a driving shaft rotatable in 45 one direction, a coaxial driven shaft rotatable in either direction, an overrunning clutch unit shiftable longitudinally of the shafts in either direction and including a pair of complementary clutch members one of which is connected to be driven 50 by the driving shaft, and means operative in response to shift of the unit in either direction to connect the two members for drive one from the other, means between the other clutch members and the driven shaft whereby when the unit is 55 shifted in one direction said driven shaft is connected to said other clutch member for drive thereby in the same direction as the driving shaft, and means between said other clutch member and the driven shaft whereby when the clutch member is shifted in the other direction the gear shaft 60 is reversely driven by said other clutch member.

CLARENCE H. BARTON.
CHARLES DREXLER.
